UNITED STATES PATENT OFFICE.

GEORGE W. COPE, OF OIL CITY, LOUISIANA.

BOILER-FEED-WATER SYSTEM.

Application filed May 6, 1922. Serial No. 558,963.

To all whom it may concern:

Be it known that I, GEORGE W. COPE, a citizen of the United States, residing at Oil City, in the parish of Caddo and State of Louisiana, have invented certain new and useful Improvements in Boiler-Feed-Water Systems, of which the following is a specification.

My invention has relation to a feeder for automatically introducing water to a boiler at stated periods, said periods being determined by the water level in the boiler, and in such connection it relates more particularly to the construction and arrangement of parts constituting such a feeder.

In the operation of steam plants, and particularly steam heating or steam supply systems, it is important that the boiler be supplied with water at required times, and it is desirable that the introduction or feeding of the water to the boiler be automatically controlled by the rise or fall of water in the boiler.

My system of feeding water to the boiler is designed to meet these requirements by the use of means of suitable construction and arrangement, and which, when properly assembled, assures absolutely and accurately the periodic discharge to the boiler of water in required volumes.

The present invention is an improvement over an application for Letters Patent for a boiler feed water system, filed October 18, 1920, Serial Number 417725, and contemplates certain changes in specified parts thereof hereinafter referred to for providing a more practical feed water system and for simplifying certain parts of the apparatus. In order that these changes and improvements may be clearly understood, a complete description of the boiler feed water system with improvements to date is given herewith.

In the carrying out of the invention, there is provided, first an elevated reservoir, or source of water supply feeding by gravity to a stationary tank elevated some distance above the water level of the boiler, and said stationary tank has a discharge pipe leading to the water chamber of the boiler, and a direct connection between the top of the tank and the steam chest or steam chamber of the boiler. This stationary tank receives and discharges at periodic intervals the water to be fed to the boiler.

Second: there is provided in connection with the charging stationary tank and its

steam connection with the boiler, a means for automatically controlling the supply of steam to the charging tank at the required period of time, said means comprising in its elementary form a water receptacle supported normally in a plane some distance above the highest level of the water in the boiler and being connected with the boiler and arranged in such manner as to cause the said water receptacle to fill from said boiler and when said water receptacle is in direct connection with the steam chest the water in the water receptacle will return to said boiler, thus causing said water receptacle to vibrate periodically and thereby control the operation of the valves on pipes conducting steam to the stationary charging tank and to the receptacle.

Third: there is provided in connection with the charging tank and the means for automatically cutting off the supply of steam to said tank, a secondary means for controlling the movement of the automatic steam cut-off means, said secondary means comprising a vessel arranged to vibrate with the fluctuations in the water level, said vessel being normally supported in a plane which is substantially the level of the water in the boiler, and connected directly with the steam chamber of the boiler and with the water chamber of said boiler by a flexible supporting means to permit of its vibration in response to fluctuations in water level in said boiler, and

Fourth: to provide in conjunction with the charging tank its valved steam supply pipe and the means for cutting off the steam supply pipe from said tank by the operation of the valves of a means to gradually apply boiler pressure of steam upon the water in said tank, said means comprising essentially a valved by-pass, the valve of said by-pass being operated previously to the operation of the valve of the steam supply pipe by said cut-off means, to lessen the volume of steam entering the tank initially.

In addition to the foregoing named instrumentalities and means, there are provided other and further details of construction of preferred form and arrangement, the nature of which will be more fully explained in the following description, taken in connection with the accompanying drawings, forming part hereof, in which—

Figure 1 is a perspective view illustrating more or less diagrammatically the arrange-

ment of a water feed system embodying the main features of my invention.

Figure 2 is a side view, partly sectioned, of the same.

5 Figure 3 is an enlarged detail view illustrating in side elevation, and in section the steam cut-off valve, the by-pass valve and connections.

10 Figure 4 is a cross-sectional view of the two-way cross fitting containing swivel couplings through which the water receptacle communicates with the boiler.

15 Figure 5 is a cross-sectional view of the jet for heating the water in the main reservoir.

20 Figure 6 is a perspective view of a check valve interposed in the pipe leading from the water chamber of the boiler to the vibrating receptacle, and

25 Figure 7 is a sectional detail view of a check valve on the charging tank.

Referring to the drawings, 1 represents the boiler and 2 the elevated feed water well or reservoir. Above the water level of 25 the boiler is located the charging tank 4, which is in direct communication at or near its base, with the well 2 by means of a stand pipe 5, the entrance end of which is preferably controlled by a check valve 6. A pipe 30 7 connects the water chamber of the boiler 1 with the tank 4, and in this pipe 7 is located a check valve 8, which permits of flow of water to, but not from the boiler 1.

35 At the top of tank 4 is located a check valve 4^a illustrated in Figure 7, opening into tank 4 and arranged to stand open by gravity. Valve 4^a serves as an air relief and to prevent a vacuum forming in tank 4, it being desirable to fill tank 4 nearly full 40 of water by gravity and to maintain a space for steam above the water level.

At the top of the charging tank 4 is located a steam pipe 11, leading from the tank 4 to the steam chamber of the boiler 1. For 45 sake of convenience, the pipe 11 is shown as entering the dome 1^a, but it may communicate with the steam chamber of boiler 1 at any desired point. On the pipe 11 is located a valve 12, the operation of which is automatically controlled as hereinafter explained.

55 The steam pipe 9 is provided with a cross fitting 13 supporting by means of stuffing boxes 14 and 15, the members 16 and 17 of a hollow frame, the members 16 and 17 tilting in the stuffing boxes 14 and 15 in the cross fitting 13. This cross fitting 13 is partitioned (see Figure 4) so as to divert the steam from the boiler through the pipes 9 and 11 by the member 16 of the hollow frame to a water receptacle 18. The hollow member 16 extends upward in water receptacle 18 in the form of a pipe 19.

60 The hollow member 17 serves as the means for permitting normally of the discharge of

water direct from the boiler 1 through pipe 17^a to the bottom of receptacle 18 and vice versa. The receptacle 18 is suspended by chain 20 passing over pulley 21, suspended preferably from pipe 11, or other fixture, 70 and having the counterweight 22 at its free end. This weight 22 is so adjusted that when receptacle 18 is nearly full of water, the receptacle will fall and will remain in its lowermost position until it has emptied 75 a portion of its contents directly into boiler 1 through pipe 17^a.

A primary exhaust pipe 25 leads from tank 4 to the elevated well or reservoir 2, and terminates in a jet 28 in well 2. A 80 weighted valve 25^a on pipe 25 is held closed under normal pressure of steam in pipe 11 when receptacle 18 descends pulling upon cord 25^b. When receptacle 18 rises the weight of the valve lever is strong enough 85 to open valve 25^a under the maximum steam pressure.

Exhaust pipe 25 being proportionately small serves to more effectually seat check valve 8.

90 The well 2 is also connected by pipe 29 with pipe 11, the pipe 29 terminating within the well 2 in a jet 30. A weighted valve 31 on pipe 29 is held closed under normal pressure of steam in pipe 11 when the receptacle 18 descends pulling upon the cord 31^a. When the receptacle rises and steam is exhausted from pipe 11 through pipe 25 and valve 25^a the weight of the valve lever is strong enough to open the valve 31 and 95 permit steam to flow to the jet 30. Exhaust pipe 29 is required only when its additional capacity is required, therefore I do not confine myself to the use of said exhaust.

100 The construction and arrangement of each jet 28 or 30 is shown in Figure 5. The pipe 25, for instance, terminates in a T 32, carrying the two branch pipes 33. This T coupling 32 is arranged within a second T coupling 34 and secured therein by the set 105 screw 35. The coupling 34 has two lateral branch pipes or tubes 36, each enclosing a pipe 38, and extending some distance beyond the same. The upper portion of the T 34 is open and encloses the pipe 25. The construction illustrated and described permits the steam to enter and mingle with water in well 2 without undue noise and agitation. I do not confine myself to the 110 use of this jet arrangement, as an ordinary jet confined in well 2 works satisfactorily.

115 In addition to the weight 22 and chain 20, and in addition to the interchange of water between the boiler 1 and receptacle 18, all of which serve to control the vibration or vertical movement of receptacle 18, there is provided a secondary means for controlling said vibrations. This means comprises a vessel 40, suspended from pipe 5, or other fixture, 120 by means of the spring 42, and resting in 130

- its depressed position in a seat 43, supported by the pipe 7. The bottom of this vessel 40 is supported by the frame consisting of the side members 44 and 44^a connected by end member 45. The end member 45 oscillates in a cross-fitting 46, and stuffing box 46^a, the fitting communicating by pipe 47 with the water chamber of boiler 1. The side member 44 is a water conveyor connecting the bottom of vessel 40 directly with the water chamber of the boiler 1, whilst the other side member 44^a is solid, and present only to complete the frame.
- The upper portion of vessel 40 communicates by a flexible pipe connection with the steam chamber of boiler 1. Such a pipe connection can be secured by preference by connecting one end of a pipe 49 by rigid elbow 48 with the vessel 40. A flexible pipe 51 connects pipe 49 with a pipe 52 entering the steam chamber of the boiler 1.
- The vessel 40 is flexibly supported at a height corresponding to the normal water level of the boiler 1, and under the varying water level in said boiler, water will flow from the boiler to the vessel 40 when the water in the boiler reaches the maximum height, and will flow back again from vessel 40 to the boiler when water level in boiler 1 is lowered and the vessel will be elevated. The vessel 40 thus vibrates, being assisted by the spring 42 by which it is supported, and the flexible connection of pipe 49 with pipe 52 permits of this vibration without breaking the steam connection between the vessel 40 and boiler 1.
- Beyond the cross fitting 46 the ends of the frame are connected by a member 53, which supports an upwardly projecting finger 54, oscillating with the frame when the vessel 40 vibrates. The finger 54 co-operates with a leg or prop 55 connected to and depending from the receptacle 18 in such a manner that when vessel 40 and its frame descend, the free end of finger 54 swings away from the prop 55, and the base or seat 56 of the finger contacts with the prop and the receptacle 18 is held in an elevated position. When, however, the vessel 40 and its frame ascend, the finger 54 forces the prop 55 out of seat 56, and permits the prop and receptacle 18 to descend.
- One of the main objects of my present invention is to relieve the stationary or charging tank 4 of the water hammer or thrust which would be caused by the sudden entrance of a large volume of steam at high speed from the pipe 11 to the tank especially during that period of time when the water in the tank is agitated.
- To accomplish this, the preferred construction and arrangement of valves and connections illustrated in detail in Figure 3 are used. The valve 12 is held on its seat or in its closed position by means of a spring 60 assisted by the steam pressure back of the valve. The valve stem 61 projects through a stuffing box 12^a and is engaged by the pivoted arm 62.
- The free end of arm 62 is connected by cord 63 with interposed spring 64, or by an elastic connection with the cross rod 65 connecting the two hollow members 16 and 17, supporting the receptacle 18. The spring 64 on cord 63 is employed in opening the valve 12 under partly balanced conditions only of steam pressure. The spring 64 therefore permits the vibration of the larger valve 12 on its seat under variations of pressure and momentum of the current of steam in the inlet pipe 11. This vibratory movement of valve 12 through spring 64 prevents the water hammer in tank 4.
- If the steam were permitted initially to pass into the tank through the main pipe 11, its entrance into said tank 4, and its condensation and rarefaction therein would cause a thrust or water hammer in tank 4, and tend to disrupt the apparatus. To compensate for this, I permit a small current of steam to enter before the valve 12 is operated. To accomplish this, a by-pass pipe 70 leads from the pipe 11 at a point in front of valve 12, and re-enters pipe 11 at a point beyond said valve 12. In pipe 70 is located a valve 71 corresponding to valve 12 in all essential particulars, having the spring 72 normally pressing the valve upon its seat, and a valve stem 73 projecting through stuffing box 74 to be operated by a lever arm 75, with the cross rod 65.
- Inasmuch as the cord or chain 76 has no spring and is not elastic, the movement downward of receptacle 18 will immediately open valve 71 before valve 12 can be operated.
- In my co-pending application referred to above, the steam pipe 9 was extended to the top of the boiler 1 for connection with the boiler's steam space and was provided with a lever-operated valve which required a gland to be packed. I have found, however, that the invention is greatly improved by having the pipe 9 considerably reduced in length and connected to the charging tank 4, and provided with a check valve 9^a. This check valve 9^a controls the opening and closing of the pipe 9. When the receptacle 18 ascends, valves 25^a and 31 open and the pressure is exhausted from tank 4, the check valve 9^a closes and condensation, decreases the pressure in receptacle 18 and the water is driven from boiler 1 through the openings in check valve 84, see Figure 6, said openings being of a predetermined size to allow the receptacle 18 to fill from boiler 1 in the time tank 4 fills from the well 2, but when the receptacle descends the valve 9^a will open and boiler pressure established in receptacle 18 and the receptacle will dis-

charge through the hand valve 85 in the time and immediately after tank 4 discharges through valve 8.

I do not confine myself to the use of valve 5 illustrated in Figure 6, as under some conditions this valve may be dispensed with.

Receptacle 18 is provided with an exhaust valve 86 which is held open when receptacle 18 is in its uppermost position, but which 10 is closed before the prop 55 contacts with the base 56. Said exhaust valve is necessary only when the temperature of the boiler room is so high that radiation will not reduce the pressure in receptacle 18 fast 15 enough to allow receptacle 18 to fill from boiler 1 in the length of time that is required for tank 4 to fill from the well 2, therefore I do not confine myself to the use of said exhaust valve.

20 In the operation of my feed water system, the charging tank 4 is fed by gravity with water from the well 2. The pressure of steam upon the water in boiler 1 will maintain the check valve 8, and pipe 7 closed 25 until tank 4 is full, or substantially full, and ready to discharge. When the water level in boiler 1 is below normal, the water in vessel 40 will flow into the boiler and said vessel will raise to release the prop 55.

30 The receptacle 18 which is full, or substantially full, of water will now descend, and in descending will operate by-pass valve 71, and main valve 12 to admit steam under pressure to tank 4. The water in tank 4 and pipe 7 is thus forced into the water chamber of the boiler, 1, the check valve 8 opening to permit the flow of the water under pressure to the water chamber of the boiler. As the water level in boiler 1 rises 35 to normal, a portion flows through pipe 47 40 into vessel 40 which then descends. The prop 55 carried by receptacle 18 is then raised, and the parts resume their former position.

45 What is claimed is--

1. In a feed water system, a boiler, a water reservoir, a stationary charging tank situated above the boiler and having a valved water inlet, a valved water discharge connection between the tank and the water space of the boiler, a valved exhaust pipe leading from the tank, an air inlet and outlet, a primary valved steam connection between the stationary charging tank and the boiler, a secondary valved steam connection between the stationary charging tank and said boiler, a vibratory receptacle the top of which has a valved steam connection with the said charging tank and the bottom of 50 which has discharge and return water connection with the boiler's water space, said vibratory receptacle arranged to receive and return water from and to the boiler, said receptacle being provided with an exhaust valve, 55 means for limiting the movement of

said vibratory receptacle, means for automatically vibrating said vibratory receptacle, means connecting the vibratory receptacle with the valve of the exhaust pipe and the valve of the primary steam connection of the stationary charging tank to thereby operate said valves, and an elastic connection between the vibratory receptacle and the valve of the secondary steam connection of the stationary charging tank to thereby effect the operation of said valve. 70 75

2. In a feed water system, a boiler, a water reservoir, a stationary charging tank situated above the boiler and having a valved water inlet, a valved water discharge between the tank and the water space of the boiler; a valved exhaust pipe leading from the tank, an air inlet and outlet, a primary valved steam connection between the stationary charging tank and said boiler, a secondary valved steam connection between the stationary charging tank and said boiler, a vibratory receptacle, the top of which has a valved steam connection with said charging tank and the bottom of which has discharge and return water connections with the boiler's water space, said vibratory receptacle arranged to receive and return water from and to the boiler, said receptacle being provided with an exhaust valve, means for limiting the movement of said vibratory receptacle, means for automatically vibrating said vibratory receptacle, means connecting the vibratory receptacle with the valve of the exhaust pipe and the valve of the primary steam connection of the stationary charging tank to thereby operate said valves, and an elastic connection between the vibratory receptacle and the valve of the secondary steam connection of the stationary charging tank to thereby affect the operation of said valve, combined with means for locking and unlocking said vibratory vessel to prevent and permit the vibration thereof. 80 85 90 95 100

3. In a feed water system a boiler, a water reservoir, a stationary charging tank situated above the boiler and having a valved water inlet, a valved water discharge connection between the tank and the water space of the boiler, a valved exhaust pipe leading from the tank, an air inlet and outlet, a primary valved steam connection between the stationary charging tank and said boiler, a secondary valved steam connection between the stationary charging tank and said boiler, a vibratory receptacle, the top of which has a valved steam connection with said charging tank and the bottom of which has a discharge and a water return connection with the boiler's water space, said vibratory receptacle arranged to receive and return water from and to the boiler, said receptacle being provided with an exhaust valve, 110 115 120 125 130

means for limiting the movement of said vibratory receptacle, means for automatically vibrating said vibratory receptacle, means connecting the vibratory receptacle with the valve of the exhaust pipe and the valve of the primary steam connection of the stationary charging tank to thereby operate said valves, and an elastic connection between the vibratory receptacle and the valve of the secondary steam connection of the stationary charging tank to thereby affect the operation of said valve, combined with means for locking and unlocking said vibratory vessel to prevent and permit its vibration, said locking and unlocking means consisting of a vessel in open communication with the water chamber and steam chamber of the boiler and arranged to vibrate in unison with the fluctuation of the water level in said water chamber to thereby start and stop the vibratory receptacle.

4. In a gravity feed water system having a stationary charging tank situated above the water level of the boiler, said charging tank provided with a valve controlled water inlet and a valve controlled water connection with the water space of the boiler, valve controlled steam exhausts from and valve controlled steam inlets to said charging tank, an air inlet and outlet, a means for periodically operating said steam valves, said means comprising a vibratory vessel having a valve controlled steam connection with the steam space of said charging tank, a discharge connection of predetermined capacity leading from the vessel to the water space of the boiler and a return water connection of predetermined capacity leading from the water space of the boiler to said vibratory vessel, said vessel being provided with an exhaust valve, combined with means for

connecting the steam valves of the charging tank with said vibratory vessel. 45

5. In a feed water system, a boiler, a water reservoir, a stationary charging tank situated above the boiler and having a valved water inlet, a valved water discharge connection between the tank and the water space of the boiler, a valved exhaust pipe leading from the tank, an air inlet and outlet, a primary valved steam connection between the stationary charging tank and said boiler, a secondary valved steam connection between the stationary charging tank and said boiler, a vibratory receptacle, the top of which has a valved steam connection with said charging tank and the bottom of which has a discharge 60 and a water return connection with the boiler's water space, said vibratory receptacle arranged to receive and return water from and to the boiler, said receptacle being provided with an exhaust valve, means 65 for limiting the movement of said vibratory receptacle, means for automatically vibrating said vibratory receptacle, means connecting the vibratory receptacle with the valve of the exhaust pipe and the 70 valve of the primary steam connection of the stationary charging tank to thereby operate said valves, and an elastic connection of 75 the charging tank to thereby affect the operation of said valve, combined with means for locking and unlocking said vibratory vessel to prevent and permit its vibration, said locking and unlocking means controlled 80 by the rise and fall of the water in the boiler.

In testimony whereof I have signed my name to this specification.

GEORGE W. COPE.
